Patented Mar. 14, 1922.

FIG. 1.

INVENTOR.
WILLIAM J. O'MARR
BY *A. B. Bonman*
ATTORNEY

UNITED STATES PATENT OFFICE.

WILLIAM J. O'MARR, OF SAN DIEGO, CALIFORNIA.

PILE-JETTING APPARATUS.

1,409,760.

Specification of Letters Patent. Patented Mar. 14, 1922.

Application filed May 5, 1919. Serial No. 294,812.

To all whom it may concern:

Be it known that I, WILLIAM J. O'MARR, a citizen of the United States, residing at San Diego, in the county of San Diego and 5 State of California, have invented a certain new and useful Pile-Jetting Apparatus, of which the following is a specification.

My invention relates to an apparatus for jetting piles and the objects of my invention are: first, to provide a jetting apparatus for jetting piles in which a plurality of jets are used in spaced relation around the pile to provide great efficiency; second, to provide an apparatus of this class whereby the 15 jets are directed to adjacent the outer edge of the pile and toward the center below said pile so that all ground beneath the pile is disturbed by the action of the jets; third, to provide a pile jet apparatus of this class 20 in which a plurality of jets may be uniformly distributed, adjacent the outer surface of the pile and in which a less number of hose connections are required for providing water under pressure to said jets; 25 fourth, to provide an apparatus of this class which is supported in position around the pile and may be turned or shifted thereon to facilitate the operation, and fifth, to provide an apparatus of this class which is very 30 simple and economical of construction, durable, easy to operate, very efficient in its action and which will not readily deteriorate or get out of order.

With these and other objects in view as 35 will appear hereinafter, my invention consists of certain novel features of construction, combination and arrangement of parts and portions as will be hereinafter described in detail and particularly set forth in the 40 appended claim, reference being had to the accompanying drawings and to the characters of reference thereon which form a part of this application, in which:

Figure 1 is a side elevational view of a 45 pile partially driven and showing my jetting apparatus in operative position thereon fragmentarily and Fig. 2 is a perspective view of the apparatus alone showing some of the members fragmentarily.

50 Similar characters of reference refer to similar parts and portions throughout the several views of the drawings.

The main conducting pipes 1 and 2, brace 3, annular conducting pipe 4 and jet conductors 5, 6, 7 and 8 constitute the principal

parts and portions of my pile jetting apparatus.

The main conducting pipes 1 and 2 are preferably provided with bends 1^a and 2^a on their upper ends which are provided with 60 hose connecting threads 1^b and 2^b and they are placed on opposite sides of the pile and parallel therewith and they are connected at their lower ends in their spaced relation by the annular conducting pipe 4 which is preferably smaller than the pipes 1 and 2 by means of reducing crosses 1^c and 2^c and mounted intermediate these crosses 1^c and 2^c on the conductor 4 are T members 6^a and 7^a 65 to which are connected the jet conductors 6 and 7. Also connected with the reducing crosses 1^c and 2^c are conductors 5 and 8 which form a continuation of the conductors 1 and 2 except that they are smaller in size 70 so that the water is conducted under pressure through the conductors 1 and 2 and then distributed to the jet conductors 5, 6, 7 and 8 the water being conducted through the pipe 4 to the conductor 6 and 7. Each of the jet conductors 5, 6, 7 and 8 are provided with jet members on their lower ends or the ends may be swaged to form jet portions and they are also provided with small outlet orifices 5^b, 6^b, and 8^b forming a small 75 jet directed inwardly for breaking up the central portion below the pile. It will be noted that this annular conducting pipe 4 is slightly larger in diameter than the pile and that several of these jet conductors 80 may communicate with this conductor 4, in 90 this case however, I have only shown two. The jet conductors 5, 6, 7 and 8 are secured in their relative spaced relation by means of an annular brace 3 which is preferably a thin plate provided with holes therein 95 adapted for the U bolts 3^a which extend around the conductors and support said conductors in a rigid manner against the brace 3.

It will be noted that in case any of the 100 driving equipment extends downwardly below the top of the pile, that the conductors 1 and 2 and conductor 4 or either of them may be offset to provide clearance for the same.

Though I have shown and described a particular construction, combination and arrangement of parts and portions I do not wish to be limited to this particular construction, combination and arrangement but 110

desire to include in the purview of my invention the construction, combination and arrangement substantially as set forth in the appended claims.

5 It is obvious that with this construction there is provided an apparatus for jetting pile wherein a plurality of jets will be distributed around the outer surfaces of the pile and inwardly and below the same where-
10 by great efficiency is provided for driving in compact earth or otherwise, that any number of jet conducting pipes may be positioned in certain spaced relation to each other around said pile and water conducted
15 to them from a less number of main conductors, that said jets may be turned around the pile in unity if desired, that the same are placed in their certain spaced relation to each other and means provided for simul-
20 tanously conducting water to all of said jets.

Having thus described my invention what I claim as new and desire to secure by Letters Patent, is:

25 A pile jetting apparatus, including a plurality of jet conductors surrounding said pile, in certain spaced relation, an annular

water conductor surrounding said pile con- siderably below the upper end of said pile in spaced relation thereto and free therefrom 30 for conducting water to the upper ends of said jet conductors, upright water conductors disposed on opposite sides of said pile provided with hose connections on their upper ends for conducting water to said an- nular conducting member, and means for bracing said jet conductors and water con- ductors in their certain spaced relation to each other comprising an annular member 35 surrounding said pile in spaced relation and free from said pile provided with **U** bolts extending over said conducting members whereby said conducting members and said annular members are rigidly secured to- 40 gether but adapted to revolve relatively to 45 said pile and to move up and down rela- tively thereto and whereby the pile may be driven on the upper end with a hammer or drop.

In testimony whereof, I have hereunto set 50 my hand at San Diego California this 26 day of April 1919.

WILLIAM J. O'MARR.
